DESIGN FOR A TEXTILE FABRIC

Jean Guy Donadieu, Jackson Heights, N. Y., assignor to Tissus Haute Couture, Inc., New York, N. Y., a corporation of New York

Application December 1, 1937, Serial No. 73,293

Term of patent 3½ years

To whom it may concern:

Be it known that I, Jean Guy Donadieu, a citizen of the United States, residing at Jackson Heights, county of Queens, and State of New York, have invented a new, original, and ornamental Design for a Textile Fabric, of which the following is a specification, reference being had to the accompanying drawing, forming part thereof, wherein—

The figure is a plan view of a textile fabric embodying my new design, the characteristic feature of which resides in the printed fringe.

I claim:

The ornamental design for a textile fabric substantially as shown and described.

JEAN GUY DONADIEU.
